Primary Examiner — Carla Jobe Wright(74) *Attorney, Agent, or Firm* — Gottlieb, Rackman & Reisman P.C.(57) **CLAIM**

The ornamental design for a mobile device case, as shown and described.

DESCRIPTION

FIG. 1 is a front, top, left perspective view of a mobile device case having the design of my invention;

FIG. 2 is a top plan view thereof;

FIG. 3 is a front elevation view thereof;

FIG. 4 is a left side elevation view thereof;

FIG. 5 is a right side elevation view thereof;

FIG. 6 is a rear elevation view thereof; and,

FIG. 7 is a bottom plan view thereof.

The stippling shows a contrast in appearance between the stippled and non-stippled surfaces.

The broken lines immediately adjacent the shaded surfaces represent boundaries of the claimed design. All other broken lines depict unclaimed environment and form no part of the claimed design.
